DESIGN FOR AN EYESHIELD

Eduard Hilgert, Brno, Czechoslovakia

Application April 23, 1934, Serial No. 51,487

Term of patent 3½ years

To all whom it may concern:

Be it known that I, Eduard Hilgert, a citizen of the Republic of Czechoslovakia and residing in the city of Brno, in the Republic of Czechoslovakia, have invented a new, original, and ornamental Design for an Eye Shield or Similar Article, of which the following is the specification, reference being had to the accompanying drawing, forming a part thereof.

On the drawing:

Fig. 1 is a top plan view of my eye shield which

comprises an irregular bow-shaped flexible blank having an integral ear engaging portion at each end thereof.

Fig. 2 is a side perspective view thereof, and illustrating the manner of mounting the same.

I claim:

The ornamental design for an eye shield or similar article, substantially as shown and described.

EDUARD HILGERT.
